C. U. SAVOYE

FEED WATER SYSTEM

Filed Feb. 26, 1923

UNITED STATES PATENT OFFICE.

CHARLES ULYSSE SAVOYE, OF HACKENSACK, NEW JERSEY, ASSIGNOR TO THE BAB-COCK & WILCOX COMPANY, OF BAYONNE, NEW JERSEY, A CORPORATION OF NEW JERSEY.

FEED-WATER SYSTEM.

Application filed February 26, 1923. Serial No. 621,492.

To all whom it may concern:

Be it known that I, CHARLES ULYSSE SAVOYE, a citizen of the United States, and a resident of Hackensack, in the county of Bergen and State of New Jersey, have invented certain new and useful Improvements in Feed-Water Systems, of which the following is a specification.

My present invention relates to feed water systems for steam power plants in which the condensate is returned to the boiler.

My invention will be best understood from the accompanying drawing, in which I have shown, more or less diagrammatically, an illustrative embodiment thereof. In said drawing, steam from a boiler 10 is led through pipe 11 to a turbine or other prime-mover 12, which, in the case shown, drives an electric generator 14. Exhaust steam from turbine 12 passes into condenser 15 and the condensate therefrom is forced from hot-well 16 and pipe 18, into one side of a feed tank 20, by pump 19, driven by motor 21. From feed tank 20, the condensate is returned to boiler 10 through pipe 30 and boiler feed pump 32.

The feed water is drawn from tank 20 by pump 52 through pipe 51 into an economizer 50, from which the heated water flows back into the other side of tank 20, the two parts of the tank being determined by a partition 55 over which there may be a flow from one side to the other, as the differential pressure between the two sides increases. A relief valve 60, in the form of a mercury trap, is provided to prevent damage in case any of the regulating devices hereinafter described, fails to operate. It will be obvious that the economizer 50 may be dispensed with and the water from tank 20 supplied directly to the boiler 10, in which case, the partition 35 will not be necessary.

For the purpose of supplying makeup water to the system, I provide a clear water reservoir 40, and water therefrom flows through pipe 42, mercury-operated U-tube valve 44 and pipe 45, into hot-well 16. The valve 44 will be described more in detail hereinafter.

Preferably, the condensate pump 19 is of sufficient capacity to handle the maximum requirements of feed water when run at a given constant speed.

In normal operation, where the condensate is just equal to the demand of the feed pump 52, the valve 44 will remain closed, and hence the connection of the hot-well 16 to the clear water reservoir 40 will be cut off. That is to say, the water from the condensate pump 19 through pipe 18 will flow through feed tank 20 through economizer 50, back to feed tank 20 and thence to the boiler. For reasons which will later be apparent, I advantageously make the feed water tank 20 closed against the atmosphere. Normally the tank 20 is maintained under a positive gauge pressure equal to any convenient value, say, five pounds above atmosphere.

I will now describe in detail valve 44 and the control means therefor. A conduit 60 is provided from feed tank 20 to a chamber 63. A conduit 64 leads from the lowermost portion 65 of the U-tube 44 to the lowermost portion 66 of chamber 63. An enlarged conduit 67, having a vertical portion 68 above the bottom 66 of chamber 63, extends to the same height as the upper portion of valve 44, as shown. The top of vertical conduit 68 is connected by a pipe 60' with clear water reservoir 40.

Sufficient mercury 70 is placed in the system, comprising chamber 70, valve 44 and pipe 67, so that upon normal operation of the power plant, i. e., when the amount of condensate equals the demand of the boiler feed pump, the mercury will extend up in pipes 64 and 65 and into the legs of U-tube valve 44 to act as a seal to prevent water flowing from clear water reservoir 40 to hot-well 16. It will be apparent that the height of the mercury columns in the legs of the U-tube 44 will be conditioned upon several factors, as, for example, the difference in height of tank 20 and clear water reservoir 40, the amount of vacuum maintained over the water in the reservoir 40, the pressure in feed tank 20, etc. It is also apparent that the height of the mercury in the vertical conduit 68 will be equal to that in the right hand leg of U-tube 44.

In case the supply of condensed steam does not equal the demand of feed pump 32, then the pressure in the closed feed tank 20 will fall, releasing some of the pressure on the surface of the mercury 70 in chamber 63. In case the diminution of pressure be

great enough, then the mercury in chamber 63 will rise to such a height as to drain the mercury from the legs of U-tube 44, thereby permitting flow of water from clear water reservoir 40, through conduit 42, U-tube 44 and pipe 45, into hot-well 16, whence it is pumped to feed tank 20 by means of condensate pump 21. The increased flow into tank 20 will raise the water level therein and thus build up the pressure therein. This pressure will act upon the surface of the mercury in chamber 70 through the medium of the water in pipe 60 and force it back into the legs of U-tube 44 (as well as pipe 68), thereby cutting off the flow of water from reservoir 40 into hot-well 16.

Conversely, when the supply of condensate is greater than the demand of boiler feed pump 32, the increase of fluid pressure upon the level of the mercury in chamber 63 by reason of the rise of the water level in tank 20, will force the mercury through pipe 64 and into the legs of U-tube 44, and will continue to force mercury out of chamber 63 until the mercury in pipes 67 and 68 have been drained. This will permit flow of water from feed tank 20 back into clear water reservoir 40, through pipe 60, tank 63 and pipes 67, 68 and 60', and this flow will continue until the pressure in feed tank 20 allows enough mercury to flow back from U-tube 44 until the end of pipe 67 in chamber 63 is again covered, when flow in pipe 60 is cut off.

It will thus be seen that I have provided a control means for the valve 44 in the supply conduit, comprising the portions 42, 45 and 18, which will operate to open said valve when the pressure in the feed tank falls below a predetermined value, and to open the valve in the conduit between the feed tank 20 and the reservoir 40 when the pressure in feed tank 20 builds up to a predetermined point, and to close both valves 44 and 63 when the pressure in the feed tank is between said valves.

It is a matter of importance that the amount of air entering the system, by being dissolved in the water fed thereto, be kept as low as possible. It will be seen that the water which is condensed in condenser 15 and returned to boiler 10, after passing through feed tank 20, is maintained in a closed system and that no opportunity is afforded for the water to come into contact with air. Any air which becomes dissolved in the condensate will be reduced to a minimum by being subjected to the vacuum in condenser 15, and removed through exhaust conduit 90 by means of condenser air pump 91. In order that the water entering the system from clear water reservoir 40 may likewise be freed of dissolved air, I provide a conduit 80 connecting the vacuum space of condenser 15 to the space above the water

level in the reservoir 40, whereby the water therein is at all times subjected to substantially the condenser vacuum.

For supplying reservoir 40 with water, I provide a valve, denoted generally by reference numeral 90, and this valve may conveniently be of a type operated by mercury, as will now be described. When the valve is in closed position, the flow of water in supply conduit 102 is prevented by the mercury partly filling a vertical pipe 92 about its point of connection to pipe 102. The top of pipe 92 is connected by pipe 93 with the air space in tank 40. The bottom of pipe 92 is connected to the bottom of a vessel 95 and a plunger 96 floats in the mercury filling this vessel. Plunger 96 is provided at its top with a chamber 97 connected with the water and the air spaces of reservoir 40 by flexible conduits 100, 101, 85 respectively. The parts are arranged so that, when the level in tank 40 is normal, mercury will cover the lower end of pipe 102, because the weight of water in chamber 97 will hold the level of the mercury in pipe 92 above that point. When the level of the water in reservoir 40 falls below normal, chamber 97 will be partially drained through flexible conduit 100. The decrease in weight on plunger 96 which is thereby occasioned will cause said plunger to rise, thereby causing a flow of mercury into chamber 95 from conduits 92 and 102, unsealing the end of pipe 102 and allowing water to flow through conduits 91, 92 and 93 into reservoir 40. As the water level in reservoir 40 rises, plunger 96 will sink in the mercury and the mercury displaced will again seal the lower end of pipe 102 to cut off the flow of water from the conduit 102. 105

Preferably, I arrange the normal water level in tank 20 so that the pressure above the water is greater than an atmosphere. This prevents the tendency to form a partial vacuum when the level falls, so that at all 110 times, a positive pressure is applied to the system, and the valves are operated by differences in this positive pressure.

It will be seen that I have provided a simple and efficient feed water system in which fluctuations of water supplied by the condenser are automatically taken care of without the use of the usual surge tank, and in which the water supplied to the boiler is maintained practically air-free. It will also 115 be noted that my control valves are operated by changes of pressures in the feed tank rather than by changes in water levels. It will also be understood that the arrangement described is merely illustrative and that the embodiment of my invention may be varied within wide limits.

I claim:—

1. In a feed water system, a steam boiler, a closed tank arranged to receive the con- 120

densate from exhaust steam, connections between said tank and the boiler, a clear water reservoir, a normally closed connection between the reservoir and the tank, and means, controlled by the pressure in said closed tank, to open the connection between the tank and the reservoir when the pressure in this tank exceeds a predetermined amount.

2. In a feed water system, a steam boiler, a closed tank arranged to receive the condensate from exhaust steam, connections between said tank and the boiler, a clear water reservoir, a normally closed connection between the reservoir and the condensate supply, and means, controlled by the pressure in said closed tank, to open said connection when the pressure in said tank is less than a predetermined amount.

3. In a feed water system, a steam boiler, a closed tank arranged to receive the condensate from exhaust steam, connections between said tank and the boiler, a clear water reservoir, connections between said reservoir and the condensate supply and between said reservoir and said closed tank, and means, controlled by the pressure in said closed tank, to close both said connections when the pressure in said tank is within predetermined limits, and to open the connection between the tank and the reservoir when the pressure exceeds such limit and to open the connection between the reservoir and the condensate supply when the pressure is less than such limits.

4. In a feed water system, a steam boiler, a closed tank, a condensate well, a constant speed pump to force water from the well to the closed tank, connections between the tank and the boiler, a clear water reservoir, a normally closed connection between the reservoir and the tank, and means, controlled by the pressure in the tank, to open the connection between the reservoir and the tank when the supply of condensate to the tank exceeds the supply from the tank to the boiler.

5. In a feed water system, a steam boiler, a closed tank, a condensate well, a constant speed pump to force water from the well to the closed tank, connections between the tank and the boiler, a clear water reservoir, a normally closed connection between the reservoir and the condensate well, and

means, controlled by the pressure in the tank, to open said connection when the supply to the boiler exceeds the supply of condensate to the well. 55

6. In a feed water system, a steam boiler, a closed condensate well arranged to receive condensed steam, a closed tank, connections between the tank and the boiler, a closed clear water reservoir, connections between the tank and the reservoir and between the well and the tank, all of said connections being arranged to maintain the water out of contact with the atmosphere, a constant speed pump to force water from the well to the tank, and a valve, controlled by the pressure in the tank to close the connection between the tank and the reservoir when the supply to the boiler equals or exceeds the supply of condensate to the tank and to open the valve when the supply of condensate to the tank exceeds the supply to the boiler, and a valve, controlled by the pressure in the tank, to close the connection between the reservoir and the well when the supply of condensate to the well equals or exceeds the supply to the boiler and to open the valve when the supply to the boiler exceeds the supply of condensate to the well. 70 75

7. In a feed water system for a steam boiler, a condenser, a closed makeup water reservoir and a conduit connecting the space above the water level in the reservoir with the vacuum space of the condenser. 85

8. In a feed water system for a steam boiler, a condenser, a closed makeup water reservoir, a conduit connecting the space above the water level in the reservoir with the vacuum space of the condenser, and means for feeding water to said reservoir constructed and arranged to maintain an approximately constant level therein. 90

9. In a feed water system for a steam boiler, a condenser, a closed makeup water reservoir, a conduit connecting the space above the water level in the reservoir with the vacuum space of the condenser, and means for feeding water to said reservoir constructed and arranged to maintain an approximately constant level therein independent of changes in pressure in said reservoir. 95 100
